3 Sheets-Sheet 2

This cross-sectional view illustrates a mechanical assembly. At the top, a gear assembly is shown with a central shaft. A lever system, consisting of a long lever 34 and a shorter lever 36, is attached to the shaft. A spring 35 is wound around the shaft, with one end attached to lever 36 and the other end attached to a fixed point. A curved arrow labeled *F* indicates an applied force. Numbered callouts point to various parts: 32 points to the top gear, 33 points to the bottom gear, 34 points to the long lever, 36 points to the shorter lever, 35 points to the spring, 31 points to the bottom gear housing, and 37 points to the curved arrow.

WINDOW SASH OPERATOR AND LOCK

Charles E. Fuller, Dothan, Ala.

Application September 16, 1947, Serial No. 774,191

6 Claims. (Cl. 268—130)

1 This invention relates to devices for raising and lowering vertically slidable window sashes and for locking them in adjusted positions.

The primary object of the present invention is to provide a device of the above kind which is simple in construction, efficient in operation, and easy to use or operate.

More specifically, the present invention contemplates a device of the above kind embodying a shaft journaled in the upper member of and extending from side to side of the window frame, sash suspension ropes adapted to be wound upon opposite end portions of said shaft and connected to the top of the associated sash respectively near opposite sides of the latter, a pulley on one end of the shaft, an endless operating cable passed around said pulley and depending at the inside of a side member of the window frame to provide a first strand adapted to be pulled to raise the sash and a second strand to control lowering of the sash, and means for normally preventing rotation of the shaft in one direction and consequent unwinding of the suspension ropes therefrom so as to lock the sash in adjusted position against lowering, said means being releasable by a pull on the second strand to permit the sash to lower.

Another object of the invention is to provide sprung pressed dogs for normally locking the lower sash against being raised, the suspension ropes for said lower sash being engaged with said dogs so as to automatically release the latter when said suspension ropes are wound upon their shaft to raise the lower sash.

Other and more specific objects and features of the invention will become apparent from the following description when considered in connection with the accompanying drawings, in which:

Figure 1 is a view, partly in elevation and partly broken away and in vertical section, of a window equipped with sash operating and locking means constructed in accordance with the present invention.

Figure 2 is a horizontal section taken on line 2—2 of Figure 1.

Figure 3 is a fragmentary vertical section taken on line 3—3 of Figure 2.

Figure 4 is a view similar to Figure 3 with the shaft shifted to permit the associated sash to lower.

Figure 5 is a fragmentary vertical section taken on line 5—5 of Figure 2.

Figure 6 is an enlarged sectional detailed view showing one of the locking dogs associated with the lower sash.

Figure 7 is a fragmentary view, partly in eleva-

2 tion and partly in section on line 7—7 of Figure 5.

Figure 8 is a fragmentary vertical section taken on line 8—8 of Figure 1.

Figure 9 is a perspective view, partly broken away, of the mounting for the shafts on which the sash suspension ropes are wound.

Figure 10 is an enlarged perspective view of one of the locking dogs for the lower sash.

Referring in detail to the drawings, F indicates a window frame having vertically slidable lower and upper sashes S and S' therein. The frame F has a hollow top member within which is fixed a shaft mount M that extends from side to side of the frame.

The shaft mount M is extensible in length so that it may be adapted to windows of different widths, and it consists of a flat tubular intermediate member 5 having flat end members 6 and 7 slidably telescoped therein. At their outer ends, the members 6 and 7 are provided with bearing brackets 8 and 9 for an extensible front roller 10 and bearing brackets 11 and 12 for a rear extensible shaft 13. The shafts 10 and 13 have reduced ends journaled in the bearing brackets, and each may consist of tubular end sections into which are telescoped opposite ends of intermediate sections 14 to permit adjustment of the shafts as to length corresponding to the adjustment of the mount M. A drum 15 and a pulley 16 are secured on one end of shaft 10, and a pulley 17 is secured on the other end of shaft 13. Pivoted at its lower end to the bracket 9 as at 18 is a link 19 in the upper end of which is journaled the end of shaft 10 which carries the pulley 16. Bracket 9 carries a stop lug 20 which limits forward swinging of link 19 to a position wherein the same is at a forward inclination as shown in Figure 4. Fixed to the back 30 of the window frame is a pointed pawl 21 arranged to engage the periphery of pulley 16 and prevent counterclockwise rotation thereof as viewed in Figures 3 and 4 when said drum is in its normal rearwardly shifted position of Figure 3. It will be understood that this end of shaft 10 may move rearwardly due to loose mounting of the opposite end of shaft 10 in bracket 8, and the parts gravitate rearwardly to the position of Figure 3 so as to normally assume such position.

When the pulley 16 and the adjacent end of shaft 10 is shifted forward as shown in Figure 3, said pulley 16 is disengaged from pawl 21 and free rotation of the pulley and shaft 10 is permitted.

Attached to and adapted to be wound upon

the opposite end-portions of shaft 10 when the latter is rotated in a clockwise direction as viewed in Figure 3, are sash suspension ropes 22 that are extended downwardly through the mount M and the top member of frame F and connected with the top of lower sash S near opposite sides of the latter. Passed several turns about the pulley 16 is an endless operating cable 23 that is extended forwardly through the inner side of frame F and then depends at the inside of the adjacent side member of the window frame to provide two strands a and b. The arrangement is such that when the strand a is pulled, the adjacent end of shaft 10 is moved forwardly from the position of Figure 3 to the position of Figure 4 so as to disengage the pulley 16 from pawl 21, and to simultaneously rotate shaft 10 in a direction to wind the ropes 22 thereon and cause the lower sash S to be raised. By pulling on both of the strands but exerting a slightly greater pull on strand b, the pulley 16 may be maintained out of engagement with pawl 21 and opposite rotation of shaft 10 permitted for allowing the lower sash S to lower. As soon as both strands a and b are released, the pulley 16 will move with the adjacent end of shaft 10 in a rearward direction from the position of Figure 4 to the position of Figure 3 so that pawl 21 engages said pulley 16 and prevents unwinding of ropes 22 to maintain the lower sash in any desired open position to which it may be adjusted. This simply prevents further lowering of the lower sash when desired, but means is provided to prevent raising of the lower sash unless the ropes 22 are wound on shaft 10. For the latter purpose, a hinged dog 24 is mounted upon the top of the lower sash adjacent each side thereof and in position to engage the adjacent side of the frame F. Each dog is normally engaged with the frame by means of a spring 25, and the adjacent rope 22 is extended freely through the dog as at 26 outwardly of its pivot. The arrangement is such that when the ropes 22 are wound upon shaft 10 the pull on said ropes acts to swing the dogs upwardly out of engagement with the frame so as to permit the lower sash to be raised. Also, the arrangement is such that as soon as the ropes 22 are slackened the dogs 24 will engage the frame and prevent raising of the lower sash. After passing through the dogs 24, the ropes 22 may be suitably anchored as by connecting the ends thereof at a point between the dogs as at 27.

Attached to and adapted to be wound upon the rear or outer shaft 10 are sash suspension ropes 28 that are extended through the mount M and the top member of frame F and connected to the top of the upper sash S' adjacent opposite sides of the latter. The ropes 28 are freely extended through eye members 29 secured to the upper corners of the upper sash and then extended inwardly from said eye members and connected together as at 30. Passed several turns about the pulley 17 is an endless operating cable 31 that is extended forwardly through the frame F and then depends at the inside of the adjacent side frame member to provide a pair of strands c and d. At its inner side, the pulley 17 is formed with a circular series of ratchet teeth 32 concentric with shaft 13. A pivoted pawl 33 is normally engaged by gravity with the teeth 32 so as to prevent rotation of shaft 13 in a direction wherein the ropes will unwind from shaft 13. At its forward end, the axle 34 of pawl 33 has a crank arm 35 provided at its free end with an eye 36 through which the strand d of

cable 31 extends. The arrangement is such that when the strand d is pulled, crank arm 35 will be actuated to swing pawl 33 out of engagement with ratchet teeth 32 so as to allow the ropes 28 to unwind from shaft 13 and thereby permit the upper sash S' to lower, the strand c being utilized to control the lowering movement of said upper sash. As soon as the pull is released on strand d, pawl 32 will gravitate into engagement with ratchet teeth 32 so as to prevent lowering of the upper sash due to unwinding of ropes 28, thereby holding the upper sash in any open position to which it may be adjusted and against further lowering. Raising of the upper sash is simply effected by pulling upon the strand c so as to rotate shaft 13 and unwind ropes 28 on the latter. At this time, the teeth 32 freely ratchet past pawl 33. In the case of each shaft, means is provided for normally preventing rotation of the associated shaft in one direction and consequently unwinding of the suspension ropes therefrom so as to lock the sash in adjusted open position against lowering, said means being releasable by pull on a certain strand of the operating cable to permit the sash to lower. Obviously, the means shown for the inner or front shaft may also be used for the rear or outer shaft, or the means shown for the rear or outer shaft may be used for the front or inner shaft. The two different means have been illustrated to simply show two of many possible modifications thereof.

By freely extending the ropes 22 and 28 through and under dogs 24 and through eyes 29, respectively, the sashes may shift laterally of said ropes to prevent binding of the sashes in the frame and insure free sliding thereof at all times. A rope 40 may be wound on drum 15 and attached to a weight 41 vertically movable in a side member of frame F to counterbalance the sash S and promote easy raising of the latter.

From the foregoing description, it is believed that the construction, operation and advantages of the present invention will be readily understood and appreciated by those skilled in the art. Changes in details of construction and further modifications are contemplated, such as fall within the scope of the invention as claimed.

Having described the invention what is claimed as new is:

1. In combination with a sash vertically slideable in a window frame having a hollow top member, a shaft journaled within the hollow member of the frame and extending from side to side of the latter, sash suspension ropes attached to and adapted to be wound upon opposite end portions of said shaft and connected to the top of the sash respectively near opposite sides of the latter, a pulley on one end of the shaft, an endless operating cable passed around said pulley and depending at the inside of a side member of the frame to provide a first strand adapted to be pulled to wind the sash suspension ropes upon said shaft and thereby raise the sash and a second strand to control unwinding of the sash suspension ropes and lowering of the sash, and means for normally preventing rotation of the shaft and unwinding of the suspension ropes therefrom so as to lock the sash in adjusted open position against lowering, said means being releasable by a pull on the second strand to permit the sash to lower.

2. The construction defined in claim 1, wherein said means comprises a pawl fixed to the frame, in combination with a mounting element for said

one end of the shaft whereby the latter normally gravitates rearwardly toward the pawl for engaging the pulley with the pawl and provides for movement of the pulley away from the pawl upon pulling said second strand.

3. The construction defined in claim 1, wherein said means comprises ratchet teeth on the inner side face of said pulley and a laterally swingable pivoted pawl normally engaged with said ratchet teeth, said pawl having a crank arm provided with any eye through which said second strand passes so that a pull on the second strand will act to swing said pawl laterally inward out of engagement with said ratchet teeth.

4. The construction defined in claim 1, in combination with spring pressed dogs mounted on the upper corners of the sash and yieldably swung downwardly into engagement with opposite sides of the frame to prevent raising of the sash, said sash suspension ropes being operatively engaged with said dogs whereby winding of said sash suspension ropes upon the shaft acts to swing the dogs upwardly out of engagement with the frame.

5. The construction defined in claim 1, wherein

said shaft is extensible, and an extensible mount for said shaft.

6. The construction defined in claim 1, wherein the sash is slidably connected to the ropes to permit lateral movement of the sash relative to said ropes and prevent binding of the sash in the frame.

CHARLES E. FULLER.
